FRANCIS H. RICHARDS, OF HARTFORD, CONNECTICUT, ASSIGNOR, BY MESNE ASSIGNMENTS,
TO AMERICAN TYPOGRAPHIC CORPORATION, A CORPORATION OF NEW JERSEY.

TYPE-BAR.

No. 919,242.

Specification of Letters Patent. Patented April 20, 1909.

Application filed May 25, 1901, Serial No. 61,837. Renewed March 10, 1909. Serial No. 482,575.

To all whom it may concern:

Be it known that I, FRANCIS H. RICHARDS, a citizen of the United States, residing at Hartford, in the county of Hartford and 5 State of Connecticut, have invented certain new and useful Improvements in Type-Bars, of which the following is a specification.

This invention relates to typebars and their manufacture, and has for its main object the provision of a typebar possessing 10 novel features and embodying a series of wrought types upon its edge adapted for use in the typographic art.

Owing to the fact that many of the types 15 used in the typographic art for printing characters are not symmetrically disposed with respect to a central reference line transverse to that line corresponding to the line of height of the resultant printed characters, there is a tendency during the action 20 of the type-forming die in the manufacture of an unsymmetrical wrought type, and especially so when the type which is to be made is located near the extreme edge of 25 the blank, for the material under the die and adjacent to this edge to flow out from beneath the die rapidly and in quantity, resulting in a type poorly formed at this point, or at least lacking in sharpness and 30 definition. The nearer the type or any portion thereof is to the extreme edge of the blank the less, manifestly, is the support afforded by the stock of the blank to the material being wrought into shape by the 35 die, and in the measure that this support is absent the less the resistance to flowage exerted by the metal. While a forming type, therefore, located in such a position on the edge of the typebar-blank that substantially 40 equal support is provided at all sides, is formed under conditions best suited to the production of a satisfactory type, on the other hand a type having a portion or portions which are necessarily located nearer 45 one extreme edge of the blank than are other portions to the opposite extreme edge is not in such a position as to be wrought into shape to the best advantage by the die.

In order to permit satisfactory types to 50 be made with equal facility and of good quality throughout irrespective of the location of each particular type or type portion, whether it be symmetrical and located centrally with respect to the blank or whether 55 it be unsymmetrical or situated more to one

side of the central reference line than the other, I provide for the purpose of manufacturing the improved typebar forming the subject-matter of the present invention a die construction and organization which 60 compensates or counteracts the undue tendency of the material to flow outward from under the die whereby when each successive die is operated by or through the action of suitable mechanism the tendency to flowage 65 on each side of the die is substantially equalized. These results I attain by so relating the inclination of opposite walls of the die with respect to the location of those walls that the nearer the corresponding 70 side of the forming type is to the extreme edge of the blank the less will be the tendency of the material in and adjacent to that edge and under the die to flow out and empty the die-cavity. 75

In the drawing accompanying the present specification, Figures 1 and 2 are plan elevational views, respectively, of a typebar embodying the present invention. Fig. 3 is a plan view upon an enlarged scale of a portion of the edge of a typebar-blank provided with a number of types, the figure representing in a conventional way, also, a pair of cutting instruments for trimming off the surplus material forced beyond the sides of 80 the blank during the operation of forming types on the edge of the latter. Fig. 4 is a cross-sectional view of a portion of the edge of the typebar-blank represented in Fig. 3, the plane of the section being that indicated 85 by the dotted line 4—4 in the latter figure and the section being viewed in the direction of the arrow adjacent to that line. Figs. 5 and 6 are views similar to Fig. 4, the planes of the sections being those indicated by the 90 dotted lines 5—5 and 6—6, respectively, and these sections being viewed in the direction of the arrows adjacent to the respective lines. Figs. 7, 8 and 9 are cross-sectional views of 95 the typebar-blank represented in Fig. 3, the planes of the sections corresponding to those of Figs. 4, 5 and 6, respectively; the scale of Figs. 7, 8 and 9 is somewhat less than that to which Figs. 4, 5 and 6 are drawn, and the dies indicated in Figs. 7, 8 and 9 are shown 100 partly in section and also by dotted lines in various positions they assume during the type-forming operation.

Similar characters of reference designate corresponding parts in all figures. 110

In the manufacture of my improved type-bar the successive types, it may be stated in a general way, result from the operation of suitable type-forming dies (designated generally by D) upon the blank which type-making members are forced one against each other in succession to cause the penetration of the blank by a selected die.

The blank, designated in a general way throughout the present specification and drawing by B, may be of any material suitable for the purpose—for instance, type-metal of proper composition brought into the requisite or desired shape in some suitable manner—for example, by casting, rolling, or otherwise. I have found, however, that a process for so operating upon the material as to produce a substantially wrought blank as distinguished from a condition resulting from the casting of the same to shape, or at least a blank having that portion or those portions wrought which are concerned in the formation of the several type-blocks, is best suited for the carrying out of the present improvements. Moreover, the blank upon which the types are to be formed may be a continuous ribbon or rod, or it may be in the form of a separate piece having a length substantially equal to the length of the finished typebar.

In effecting the penetration of the material of the blank by the die it is immaterial whether the movement, which I may designate as a transverse feeding movement, is imparted to the blank or die or to both, but I find it convenient to feed the blank against the die. This feeding movement of the die and blank toward and against each other is not the only movement, however, utilized in forming my improved typebar and for facilitating the filling of each respective die-cavity or die-space, for removing the excess or surplus material separated or sheared from the type-block during the type-forming operation and for producing a compact and dense condition of the various surfaces, but in combination with this movement there is a relative subsidiary movement imparted to the members which combined motion operates to produce a type gradually and by a series of reductions to accomplish a coincident and progressive working outward of the excess material. This subsidiary movement operates in conjunction with the aforesaid feeding movement to force excess material away from an adjacent type during the making of the type-bar—that is, crosswise or laterally of the blank—and for further protecting this already formed type I preferably use a wall or plate adapted to enter into the comparatively narrow space between the finished type and the material under the working die in which position it remains during the type-forming operation, serving

as a retaining surface against which the moving material or flowage is received and by which it is effectually directed. Such wall, it is evident, so far as the purposes it fulfills are concerned, may be separate from the die and operated independently thereof, but I find it convenient to attach it to the die and operate the two as a unit, while the subsidiary movement operating to gradually form a type and work excess material outward transversely of the blank, moreover, preferably reverses in direction alternately, for the reason that such alternating motion is conveniently attained and is best adapted to produce a symmetrically formed type. In other words, a relative to-and-fro movement is imparted to the members (the blank and the die) during the period of type-forming, and for the purposes of the present specification I have represented, in Figs. 7, 8 and 9, the die as having a rocking motion which may be conveniently attained by imparting such motion to a proper die-carrier. The wall previously mentioned as being provided for the purpose of protecting an adjacent type and which insures the ordinary type-separating space is located at the rear side of the type-making die. The die may also (although its presence is by no means essential to the practice of the present invention) be provided on the opposite side with a space-forming die whose width is considerably more than the corresponding dimension of said retaining wall, and which serves during the operation of the die on the blank to form a space in advance of the type considerably wider than this space will be eventually when the next type is formed. The purpose of this latter feature is more clearly set forth in my application Serial No. 57,934, filed April 29, 1901, to which reference may be had for a more detailed explanation of the objects sought thereby and the advantages resulting from its employment.

The various operative mechanical details and mechanisms which are adapted to effect a proper relative movement of the type-making members may be of various sorts and operative in any suitable and proper manner for effecting the penetration of the appropriate portion of the blank to secure the desired sequence in the composition.

In general, the various characters of a line of typographic composition are, in comparison one with the other, differently disposed with respect to arbitrary and parallel, longitudinal lines between which are included the characters of the line. In other words, some of the types for producing characters are centrally disposed in the space between the said boundary lines, while other types are located nearer one line than the other. Assuming that these boundary lines represent approximately the longitudinal edges of a

typebar-blank, it is evident, that some of the types in the typebar made therefrom are necessarily located nearer one extreme edge of the bar than the other, or at least have 5 that portion of their body contiguous to one extreme edge nearer to the latter than the distance between the other extreme edge and the portion of the type body adjacent thereto. The result of this variation in position 10 of the type bodies with respect to the extreme edges of the blank, gives rise to a tendency on the part of the material under the working die, during the penetration of the blank by the latter to flow outward with 15 greater facility from that portion of the forming type which lies nearest to one or the other of the two sides of the blank and as a result of the flowage induced by the type-formative stresses, the moving material carries 20 with it a portion of the mass within the cavity of the die, tending thereby to empty that particular locality therein which is adjacent to the nearer edge. I have found that this tendency is eliminated or obviated 25 to a very great extent by making the side of the die—that is, that peculiar wall thereof adjacent to the side of the blank—more nearly parallel to such side measured depthwise of the blank, the nearer the die is situated 30 to the side of the blank during the type-forming operation. This making of the wall of the die more nearly parallel to the side of the blank has the effect of holding metal in the die against so free a flowage therefrom, 35 thus in a measure reducing the otherwise excessive tendency of the metal in the flowage stream below the die from dragging metal necessary for the formation of the type-block outwardly and downwardly and emptying 40 thereby the die-space of some of the metal previously forced upward into said space. I have found, furthermore, that by thus making the side wall of the die more nearly parallel with the vertical height of the type 45 body in proportion as the type-face extends more nearly to the side of the blank, the movement of the different parts of the metal are regulated and controlled with the effect of materially promoting the efficiency of the 50 die action and increasing the perfection of the product with a given amount of die action on the blank. Thus, taking the "1", "o", and "y" as typical of these various 55 relative positions existing in the typographic art, and consequently in the manufacture of a wrought typebar from a typebar blank, the "1" as shown in Fig. 3 extends nearly to one extreme edge of the blank, while the "y" extends nearer to the opposite extreme 60 edge and the "o" is centrally located. The material under the respective dies during the action of the latter in forming their corresponding types flows toward the outer side of the typebar-blank tending to remove a 65 portion of the total mass within the die nec-

essary to form and build up the complete type-block. This tendency I diminish or suppress by making that wall of the die which serves to form the face of the type-block at the nearer edge more nearly parallel to the vertical axis of the die, see particularly the wall 2 in Fig. 7, which figure represents a suitable die for forming the "1", as compared with the inclination of the opposite wall 3, and in the relative inclination of the walls of the die for forming the "y"—that is, the angles made by the walls 2' and 3' with the axis of the die in Fig. 9. As regards the "o", it is evident from an examination of Figs. 3 and 8 that in this 80 particular style of type the "o" is centrally located with respect to the extreme edges of the blank, and hence the inclination of the walls 3'' and 2'' may be the same with respect to the axis of the die. 85

In the style of type-blocks represented the more nearly vertical face of the opposite faces herein specified does not extend the entire distance to the impression or type face, but is connected therewith—in some of 90 the blocks by a short face y or y' , which, of course, implies a corresponding conformation of the interior faces of the corresponding dies.

The dies D for producing the several 95 types used in composition may be brought into proper relation to the type-blank by hand or by mechanism operating or operated to attain the desired sequence. The machine ordinarily used for making the 100 present typebar will embody therefor a series of selective dies combined with mechanism for bringing the blank and each selected die in proper relation to form types located in proper positions on the blank. 105

With respect to the direction, rapidity, and extent of the transverse feeding movement and the oscillatory movement and the relation of these various factors to each other, as well as the relation of the two 110 specified movements one to the other, these may be varied in any desired manner. The duration of the oscillatory movement may be embraced, for instance, within the limits of the period in which the members are fed toward and against each other, but preferably the oscillation will commence after the type has been partially formed and cease just before the feed movement terminates. Furthermore, both movements may be uniform throughout their whole duration or either may be varied or they may both be varied. 115 120

With respect to an appropriate interrelation, I have found good results to follow 125 from the gradual reduction of the transverse feeding movement during the latter portion of such movement accompanied by a concurrent oscillatory movement decreasing in amplitude or extent of oscillation 130

during the later stages of the feeding movement, ceasing altogether just prior to the termination of the latter.

The action to which the material under 5 the die, considered in its entirety, is subjected as a result of the oscillatory movement when the blank is under the compression of the die may be described as a rolling action. As the die advances into the material of the blank and the oscillation from 10 side to side takes place, indicated in a general way by the dotted positions D' , D'' of the dies, more and more of the material is forced into the die-cavity and subjected to 15 the forging and swaging action of the walls and faces of such cavity. More and more of the material necessary to build up and form the type-block, as the edges of the outer portion of the die alternately bite 20 afresh into the blank, is forced or squeezed upward into the die and under the impact and pressure of the interior faces of the die, as the relative inclination of these faces to the surfaces of the mass changes, by reason 25 of the oscillatory movement, the material is forged and wrought to form, while the faces at the bottom of the die-cavity serve to swage the upper portion of the type-block 30 constituting the type face to shape.

When the type-block as it is being formed is located adjacent to the extreme edge of the typebar-blank, the wall of the die close to the latter being made more nearly parallel to the side face of the blank—that is, 35 extending more in the direction of the die movement as compared with the other wall—presents less horizontal surface to the material, the effect of which is to confine the force urging the material downward to 40 the outside of the die and to lessen the pressure on the mass within the die. The stresses tending to induce flowage are therefore greatest at the outside of the die and the flowage movement within the mass of 45 the die-cavity is reduced in proportion as the wall of the cavity is made more nearly to coincide with the direction in which the die is fed.

The action to which the material of the 50 blank is subjected is one effecting a gradual reduction thereof, operating, moreover, to compact the material of the type-block and render the surfaces smooth and unbroken and to connect them one with the other in a 55 manner precisely conforming to the boundary edges or lines of intersection between the planes of the corresponding faces of the die. Furthermore, the forging operation results in the strengthening of the integral connection of the block with the stock of the blank, 60 while, during the oscillatory movement, first on one side and then on the other, an outlet is created by reason of the slight separation of the material from the faces of the die 65 through which air confined in the latter may

escape and oil, grease and other foreign matter may be squeezed out, assisting by this action in forming an exact counterpart of the type-forming die.

I find it convenient to remove those portions of the edge of the blank at the sides of the type-block and adjacent to the sides of the working die concurrently with the formation of the type-block, and I utilize for this purpose the described oscillatory motion 70 to gradually work such material outward laterally of the blank. The crosswise movement of this material is effectively accomplished by presenting to the material at such points where movement or flow is required— 75 that is, at the sides of the die—a relatively fixed surface or surfaces which as the result of the oscillatory motion works the material under it outwardly by pressing on the same. Such surfaces, it is manifest, may be independent of the die, but for the sake of convenience they may be connected therewith and may in fact be formed by the surfaces of integral extensions of the die body. They 80 are here so represented, (see particularly the 85 surface of the extensions $4'$, $4''$, of the die,) the lower edge of the retaining wall already mentioned as serving to confine the material endwise of the blank being also utilized for displacing the material to some extent if it is 90 desired to form a typebar with deep recesses between the types as shown at α in the illustrated bar.

The material forced beyond the planes of the sides of the typebar by the operation of 100 the dies may be trimmed off and removed to bring the sides of the bar into substantial parallelism by some suitable means—such, for instance, as cutting instruments $c-c$, shown in a conventional way in Fig. 3. Thus, 105 within limits, there is provided according to the present invention an organization of die-walls or faces for the production of consecutive types which permit the dies to be operated at any portion of the edge of the blank 110 with reference to the position of the die transverse of the blank edge. In other words, by adapting the relation of the wall of the die to the particular position transversely of the blank assumed by the die when working, 115 the facility with which the material flows downward under the action of the advancing die is substantially equalized for the two sides of the blank whether the extreme edges of the latter are located at the same distance 120 from those walls or whether they are located at unequal distances therefrom.

The spaces between the types of words or letters, whether such spaces be of uniform width or otherwise, may be made in any suitable manner, but preferably they will be formed by a suitable die or dies operating to remove portions of the edge of the blank sidewise of the latter and form spaces by a 125 rolling action, as already described. 130

Having described my invention, I claim—

1. The type bar herein described embodying a body portion and a series of forged types thereon, the printing faces of said types extending different distances toward the sides of said body portion and those ends of the types which are most adjacent to such sides being of less inclination to the perpendicular of the printing face than are the more remote ends.

2. As an article of manufacture, a type bar body portion having a series of wrought type blocks surmounted by type faces, said type faces being disposed at different relative distances from the sides of the body portion throughout said series and the ends of the blocks supporting those type ends which more nearly approach the sides of the body being disposed at a less angle to the perpendicular of the type face than are the other ends of the blocks.

3. As an article of manufacture, a type bar having upon its edge a line of type blocks surmounted by type faces, some of said type blocks having one end of the type face located nearer one edge or side of the type bar than is the other end and the end walls of said blocks which are nearer the side or edge of the type bar being of less inclination to the perpendicular of the type face than are the other end walls of said

blocks, and said type blocks being of uniform density throughout their entire type faces.

4. A type bar having type thereon, one or more of such type having one or more of its end faces inclined to the sides of said bar, the nearer the end face of a type to the edge of the bar the less the inclination of such face.

5. A type bar having type thereon, each having one or more of its end faces inclined to the sides of said bar, the inclined faces of those type nearest to the edge of the bar having less inclination than the inclined faces of companion type.

6. A type bar having type thereon, the end faces of some of which have a different inclination with relation to the sides of said bar than the end faces of companion type.

7. A type bar having type thereon, the end faces of some of which have a different inclination with relation to the sides of said bar than the end faces of companion type, the nearer such inclined end faces to the edge of the bar the less the inclination of such faces relatively to the sides of such bar.
